UNITED STATES PATENT OFFICE.

WILLIAM H. CROSBY, OF CORNING, NEW YORK.

WASHING DEVICE FOR AUTOS.

1,394,282.

Specification of Letters Patent. Patented Oct. 18, 1921.

Application filed April 26, 1920. Serial No. 376,826.

To all whom it may concern:

Be it known that I, WILLIAM H. CROSBY, a citizen of the United States, residing at Corning, in the county of Steuben and State 5 of New York, have invented new and useful Improvements in Washing Devices for Autos, of which the following is a specification.

The present invention relates to a vehicle 10 washing apparatus.

The primary object is to produce a simple means whereby water or other cleansing fluid is caused to pass through a porous rubbing or cleansing element to which is 15 attached a handle portion which is grasped by the operator to direct the cleaning element and the fluid passing therethrough to the several parts of the vehicle to be cleaned without necessitating the wetting of the 20 operator's hand.

A further object of the invention is to produce a vehicle cleaning apparatus which shall be of a construction to permit of a 25 cleaning fluid and a rubbing surface entering between parts of the vehicle which could not be conveniently reached by hand, and one wherein the operator need not contact with either the cleaning surface or with the fluid which passes through the cleaning 30 surface.

A further object is to produce a vehicle cleaning apparatus in which a flexible pipe is connected to a source of water supply, the said pipe in turn being connected to a handle 35 through which passes a tube that enters a porous cleaning element, such as a sponge, means also entering the sponge, surrounding the tube and having a locking engagement with the handle for sustaining the 40 cleaning element on the tube and connected with the handle, said means also permitting the ready removal of the cleansing element for the cleaning of the latter. The foregoing objects, and others which will appear 45 as the nature of the invention is better understood, may be accomplished by a construction, combination and operative arrangement of parts, such as is disclosed by the drawings.

50 In the drawings:—

Figure 1 is an elevation of the complete apparatus.

Fig. 2 is a plan view of the handle end portion thereof.

55 Fig. 3 is a sectional view approximately on the line 3—3 of Fig. 2.

Fig. 4 is a sectional view approximately on the line 4—4 of Fig. 3, the dotted lines showing the position of the parts of the sponge or cleansing element holding device 60 when the nozzle end of the construction is to be inserted in or removed from the said sponge or cleansing element.

Fig. 5 is a sectional view approximately on 65 the line 5—5 of Fig. 2.

The numeral 1 designates a faucet connected with the source of water supply. The numeral 2 designates a flexible hose that has one of its ends connected by a suitable coupling to the faucet. The opposite or outer end of the hose carries the interiorly threaded element of a coupling, the exteriorly threaded element of the said coupling, indicated by the numeral 3 being carried by a valve controlled nozzle 4. The nozzle is connected by a flexible hose 5 through the medium of a clamp or coupling 6 to a pipe member 7. The pipe passes centrally through the handle member 8 of the improvement, and is secured in the handle in any desired or preferred manner. The portion of the pipe that projects through the outer end of the handle provides what I will term the nozzle end of the said pipe, and the same is preferably arranged at a slight inclination with 75 respect to the pipe proper. This nozzle end, indicated for distinction by the numeral 9, has adjacent to its outer portions radially disposed apertures 10, and its open outer end incut transversely and the overlying 80 portions provided by the said cuts are slightly flattened from the outer end or nozzle with oppositely disposed angular lips 11.

On the outer end of the handle 8 there is 85 secured a cap 12. This cap has its outer closed end provided with spaced openings 13, and the handle has longitudinal depressions 14 which are of a greater area and which surround the walls provided by the 90 openings 13.

The cleansing element, indicated by the numeral 15, is in the present instance in the nature of a sponge or other porous element and is slotted longitudinally through one of its edges to provide an interior pocket 16. In this pocket is received the nozzle 9 and the bail shaped portion 17 of the expandible element which holds the sponge on the device. The bail or U-shaped portion 110 of the holding element has its side members extended inwardly as at 18 toward each

other and from thence provided with parallel extensions in the nature of arms 19. The holding member is constructed of spring wire, and the arms 19 have their outer 5 surfaces provided with oppositely disposed notches 20. The arms are disposed to pass through the openings 13 in the cap 12, and when in this position the central and outer portion of the bail 17 is received between 10 the lips 11 of the nozzle, thus the bail partly closes the outer open end of the nozzle.

Slidably mounted on the arms 19, and also received on the pipe member 7 inward of the 15 nozzle end thereof, is a spreader member 21. The spreader member is in the nature of a flat plate and is provided with openings through which the arms of the holder member pass and through which the pipe 7 also 20 passes. The openings through which the arms 19 pass are indicated by the numeral 22, and these openings are located a distance away from each other greater than the distance between the openings 13 in the cap 25 12. It will thus be obvious that by forcing the spreader member toward and against the outer and closed end of the cap the arms 19 will be spread away from each other, causing the notched portions thereof to engage 30 with the outer walls provided by the openings 13 in the cap 12. In a like manner the side portions of the bail end of the holding device will be also spread away from each other, causing these portions to 35 contact with the side walls provided in the pocket 16 of the sponge, and thus effectively holding the sponge on the device.

By reference to the drawings it will be seen that the sponge member is substantially 40 elliptical in plan and is rounded from its body to the central portion of its edges. The sponge is comparatively thin in cross section. The water delivered through the pipe and nozzle will saturate the sponge, 45 and the comparatively broad outer face of the sponge may be applied for rubbing and cleaning flat or almost flat surfaces of a vehicle, while the rounded edges of the sponge may be inserted between 50 spokes at their juncture with the hubs of the wheels, and any other parts of the vehicle where it is extremely difficult to reach in the usual manner. The operator at

all times grasps the handle, and by regulating the valve 4 in the nozzle, which is 55 located conveniently with respect to the handle, the flow of water through the sponge may be regulated, and it is thought that the foregoing description, when taken in connection with the drawings will fully set 60 forth the construction, combination and operation and advantages of the improvement.

In practice I have found it desirable to secure the sponge to the holding element after the latter has been inserted in the slit 65 of the former and after the latter has expanded to contact with the walls made by the slit. By such arrangement I am enabled to employ sponges or other cleaning elements of a determined or desired quality, 70 so that the purchaser thereof will be assured that he is obtaining an article best suited for the work to be performed thereby.

Having thus described the invention, what I claim is:—

75

1. A device of the class described comprising a water conducting pipe terminating in an apertured nozzle having its outer end lipped, a handle surrounding and fixed to the pipe, a cap secured to its outer end and having a plurality of openings therethrough, a bail-shaped holder member carried by said handle and having its arms provided with outwardly disposed notches adjacent to their ends, and means slidably mounted on the 80 pipe for spreading the arms of the holder member away from each other and forcing the notches thereof into locking engagement with the cap aforesaid.

2. A water conducting pipe terminating 90 in an apertured nozzle having its outer end lipped, a handle secured to said pipe and having a plurality of longitudinal openings therein, a cap secured to its outer end and having a plurality of openings therethrough 95 in alignment with the openings in said handle, a bail shaped holder member received between the lips of the nozzle and having its arms extending through the openings in said cap and into the openings in said handle and means slidably mounted on said pipe for spreading the arms of the bail-shaped holder member into locking engagement 100 with the cap aforesaid.

In testimony whereof I affix my signature. 105
WILLIAM H. CROSBY.
